RAILWAY CAR VESTIBULE DIAPHRAGM

Hugh H. Hendrickson, Elkhart, Ind., assignor to
The Adlake Company, Chicago, Ill., a corpora-
tion of Illinois

Application May 13, 1936, Serial No. 79,561

4 Claims. (Cl. 105—15)

This invention has to do with the diaphragms which are used in forming the closed passageways between adjoining railway cars, and is particularly concerned with the problem of preventing such diaphragms from sagging intermediate their ends when made of flexible material in a number of small pleats.

The purpose of the invention is to provide, in association with a diaphragm, improved means 10 in the form of a flexible cable threaded through the diaphragm and maintained substantially straight by the action of a spring, for supporting the diaphragm against sagging without interfering in any way with the normal extension and 15 contraction of the diaphragm.

Other more specific objects and advantages will be apparent to those skilled in the art upon a full understanding of the construction, arrangement and operation of the supporting 20 means which constitutes the invention.

Two slightly different embodiments of the invention are presented herein for the purpose of exemplification, but it will of course be appreciated that the invention may be incorporated in other structurally modified forms coming equally 25 within the scope of the appended claims.

In the accompanying drawings:

Fig. 1 is a vertical section through concentrically arranged inner and outer diaphragms connecting the vestibules of adjoining railway cars;

Fig. 2 is a horizontal section through one side of the diaphragm assembly, taken on the line 2—2 of Fig. 1;

Fig. 3 is an inside face view of the lower portion of one side of the outer diaphragm;

Fig. 4 is a vertical section through similar diaphragms connecting the vestibules of adjoining railway cars of a different type, showing but one side of the assembly; and

Fig. 5 is a horizontal section through the side of the assembly shown in Fig. 4, taken on the line 5—5 of Fig. 4.

The diaphragm assembly which is shown in Figs. 1 to 3 inclusive is intended for application to articulated cars of streamlined trains, where the cars are more or less permanently joined together at their ends. In this type of construction the usual face plates beyond the end frames 10 of the cars are omitted, and the diaphragms—50 in this instance a single outer diaphragm 11 and a single inner diaphragm 12—extend without interruption from the end frame 10 of one car to the end frame 10 of the adjoining car.

The outer diaphragm 11 is arched in form and is 55 disposed with its sides 13 and top 14 substantially

even with the sides and top of each of the cars. The inner diaphragm 12 is also arched in form and is disposed with its sides 15 and top 16 substantially even with the sides and top of the passageway 17 between the cars. The passageway 5 17 between the cars is defined by the inner dia- phragm 12.

The diaphragms 11 and 12 are made of heavy fabric, or other suitable material, in a number of pleats 18, which pleats are so constructed and 10 arranged as to permit the diaphragms to expand or contract freely within wide limits without buckling. Certain of the pleats 18 of both dia- phragms are riveted or otherwise attached along their edges to arched trusses 19 of aluminum or 15 other suitable material, which trusses, like the pleats to which they are attached, extend across the tops of the diaphragms and down the sides thereof. The trusses for the outer diaphragms are placed on the inside, while the trusses for 20 the inner diaphragms are placed on the outside.

These trusses are preferably located at about every third pleat, but a larger or smaller number of them may be employed, depending on the stiffness of the material of the diaphragms and 25 size of the pleats formed therein. The lower ends of the trusses terminate slightly above the lower edges of the sides of the diaphragms, which lower edges are preferably finished off with wear strips 20 of some soft yieldable material such as 30 chrome, leather or sponge rubber. The strips 20 serve to prevent the diaphragms from buckling vertically upon contact with the underlying floor plates in the passageway 17.

The trusses 19 are provided with eyelets 21 in 35 both sides thereof, with the eyelets in the differ- ent trusses of each diaphragm in substantial register with each other. These eyelets are strung on flexible metal cables 22 which extend horizontally along the vertical sides of the dia- phragms, preferentially near the lower edges of 40 the same, from the end frame 10 on one car to the end frame 10 on the adjoining car. At the end frames the cables 22 are trained about pulleys 23 which are hinged on vertical pivots to 45 brackets 24 connected to the end frames. Be- yond the pulleys the cables 22 extend upwardly at right angles to the horizontal stretches of the cables and are attached some distance above the pulleys to the lower ends of coil springs 25 con- 50 nected to the end frames. While two springs are preferably used at the ends of each cable, one of the springs can be omitted, if desired.

The springs 25 are made long enough and strong enough to keep the cables 22 under sub- 55

stantial tension in the most contracted positions of the diaphragms, with the result that the trusses 19 through which the horizontal stretches of the cables are threaded will be kept substantially in horizontal register with each other and the diaphragms will thereby be prevented from sagging to any appreciable extent intermediate their ends, all without interfering in any way with free expansion and contraction of the diaphragms. A spring tension on the cables of about 200 pounds will give good results and will also prevent the diaphragm side walls from giving way should a person be thrown sidewise against the same when passing through the passageway 17 between the cars.

In the modification which is shown in Figs. 4 and 5, the diaphragms do not extend continuously from one car to the next but are individual to each of the cars and terminate at face plates which are brought together when the cars are coupled, the registering inner diaphragms 26 of both cars being connected to face plates 27 and the registering outer diaphragms 28 of both cars being connected to supplemental face plates 29.

In this modification only the outer diaphragms 28 are of sufficient length to require any intermediate support. The spring tensioned cables 30 for the outer diaphragms operate between the end frames 31 and the face plates 29, so as not to interfere with the coupling and uncoupling of the cars, and only one spring is employed with each cable.

I claim:

1. The combination with an extensible diaphragm, of spring tensioned cables extending horizontally through guides associated with the sides of the diaphragm intermediate its ends for supporting the diaphragm intermediate its ends, and means at the ends of the diaphragm for supporting the spring-tensioned cables.
2. In car construction, upright passageway members which are movable toward and away from each other, a diaphragm which is connected to the members and is provided with pleats for

permitting of expansion and contraction in conformity with the movement of the members, and means for supporting the diaphragm intermediate the members comprising a cable which extends from one of the members to the other through an aperture in the diaphragm, and a take-up device associated with the cable for keeping the latter taut and substantially straight in all positions of the members.

3. In car construction, upright passageway members which are movable toward and away from each other, a diaphragm of inverted U-shaped cross section which is connected to the members and is provided with pleats for permitting of expansion and contraction in conformity with the movement of the members, and means for supporting the diaphragm intermediate the members comprising cables which extend horizontally from one of the members to the other at the sides of the diaphragm through apertures in the latter and springs connected with the cables for keeping the latter taut and substantially straight in all positions of the members.

4. In car construction, upright passageway members which are movable toward and away from each other, a diaphragm of inverted U-shaped cross section which is connected to the members and is provided with pleats for permitting of expansion and contraction in conformity with the movement of the members, and means for supporting the diaphragm intermediate the members comprising trusses attached to certain of the pleats, cables which extend horizontally from one of the members to the other at the sides of the diaphragm through apertures in the trusses, pulleys on the members about which the cables are trained, and springs connected with the cables and the members beyond the pulleys at right angles to the horizontal portions of the cables for keeping the latter taut and substantially straight in all positions of the members.

HUGH H. HENDRICKSON.
